CLAIM

The ornamental design for a concealment box, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of a concealment box in a closed configuration, showing my new design;

FIG. 2 is a top plan view thereof;

FIG. 3 is a rear elevation view thereof; and,

FIG. 4 is another perspective view thereof, shown in an open configuration.

All surfaces not shown form no part of the claimed design.

1 Claim, 3 Drawing Sheets
